MECHANISM FOR PRODUCING PRINTING PLATES BY ELECTRIC ARCS

Joseph A. Bennett, Bloomington, Ind., assignor of one-half to Joseph W. Piercy, Bloomington, Ind.

Application October 31, 1933, Serial No. 696,096

24 Claims. (Cl. 178—5)

This invention relates to a method and apparatus for producing printing plates and producing these printing plates as exact copies of either negatives or positives and particularly to means for producing a plate in correspondence with variations of a light responsive element such as a phototron affected by radio waves induced from a distance or affected by variations of light passing through a negative or reflected from a positive.

This invention depends upon the action of an electric arc or rather a plurality of rapidly successive arcs formed between the plate and a tool which cause the molecular construction of the immediate area at which the arc is formed on the plate to be affected and cause an ionization of the molecules of the metal of the plate which flow to the stylus or tool, the metal of the plate becoming oxidized and deposited on the stylus in the form of an oxide which is dissipated by the heat of the stylus. The metal is thus bitten out in the same sense that it is bitten out by acid in the process of etching and that just as the uncovered metal of an etching plate becomes chemically combined with the etching acid and is carried away from the etching plate, itself, so the metal on the plate 41 is oxidized and carried away at successive points by the successive arcs.

The general object of the present invention is to provide a printing plate producing machine of the character stated which will reproduce upon a printed plate masses of pure black, masses of pure white and intermediate tones grading by fine degrees into the pure black or into pure white and provide for this purpose an electric arc acting upon the plate and controlled by the light-responsive element or phototron, the intensity of the arc varying with the light variations of the negative or picture to be reproduced and the arc thus forming pits in the plate, the size of the pits depending upon the intensity of the arc.

A further object is to provide a mechanism of this character in which the picture to be reproduced is scanned between a source of light and a phototron or other light-sensitive element by a rectilinear movement of the negative in one direction and a step by step traversing movement of the negative in the other direction, the stylus or other element producing the arc being correspondingly traversed longitudinally and laterally across the plate to be engraved, the mechanism for producing the longitudinal and transverse traverse of the negative and the arc pro-

ducing pencil being of the general character shown in my prior application for patent on Machines for reproducing printing plates for pictures, filed June 23, 1932, Serial No. 619,716.

A further object is to provide a mechanism of this general character which is capable of reproducing line cuts and another mechanism having the same general characteristics but in detail somewhat different from the first named mechanism for the purpose of reproducing half-tones.

Other objects will appear in the course of the following description.

My invention is illustrated in the accompanying drawings, wherein:

Figure 1 is a side elevation of my printing plate producing mechanism, the amplifier system being shown diagrammatically;

Figure 2 is an enlarged elevation of the tool carrying head, the metallic plate and the support therefor being shown in section;

Figure 3 is a fragmentary top plan view of the negative support carried upon the ram;

Figure 4 is a diagrammatic elevation showing another form of tool head particularly adapted for half tone work.

In the accompanying drawings, I have illustrated generally a mechanism for reciprocating the negative and the arc-forming pencil or stylus which is illustrated in detail in my before mentioned application and which includes a longitudinally movable bar or ram designated 10 operating within guides 11 carried by a supporting frame. Disposed above the supporting frame and carried thereby is a gear wheel 12 which through an intermediate gear wheel 13 is driven by a driving pinion 14 connected to a motor or any other source of power, this motor continually operating while the engraving is being done. The shaft 15 upon which the gear wheel 12 is mounted carries upon it the diametrically grooved wheel 16, the groove of which is designated 17 and mounted upon the portion 11a of the frame is a swinging arm 18 which is pivoted intermediate its ends to a block 19 adjustably mounted within the groove 17. The depending free end of this arm is connected by a link 20 to upwardly extending ears 21 mounted upon the ram. The arm 18 is longitudinally slotted and the bolt 21 which connects the arm to the block 19 slides in this longitudinally extending slot. It will thus be seen that as the wheel 16 rotates, the arm will be given an oscillatory movement and the ram will be reciprocated to an extent depending upon the adjust-

ment of the block 19 nearer to or further from the shaft 15.

For the purpose of giving a transverse traverse to the carriage, which includes the guides 11 and 5 the ram 10 and the parts supported thereon, I provide a traversing screw 23 which is mounted in the ends of the frame and at one end carries upon it the two reversely notched ratchet wheels 24 and 25. The shaft also carries upon it the 10 handle 26 whereby the screw shaft may be rotated by hand to retract the carriage to its initial position.

Mounted upon the ratchet end of the shaft 23 is an oscillating arm 27 carrying the double 15 pawls 28 and 29, these pawls coacting respectively with the ratchets 24 and 25. The arm 27 is oscillated by means of the link 30 engaging with the pin 31 mounted in a block 32 transversely adjustable in a slot 33 formed in the face 20 of the gear wheel 34, this gear wheel being driven by pinion 16. Thus a greater or less rotative movement may be communicated to the feed screw 46 so that the step by step traversing movement of the arc forming stylus across the 25 face of the plate will be very slight or relatively coarse. A single traverse step is made upon the return movement of the ram 10 to its initial position. Thus the arc forming stylus moves in one direction along the plate the full length of 30 the stroke for which it is adjusted and is then retracted and or as when it is retracted, it is given a lateral movement of one step and then again moves longitudinally across the face of the plate.

35 The negative supporting means may be of any suitable character and is carried by the ram but is shown as a table 35 having thereon a rotatable plate 36 formed with an opening or recess within which the negative 37 may be disposed, this plate 40 being so arranged that the plate may be rotated through a quarter of a circle. Suitable masking means may be provided for this as disclosed in my prior application.

Mounted upon the ram 10 at the end of the 45 ram opposite the support for the negative is a tool controlling head and disposed below the tool controlling head is a frame or clamp designated generally 38 for supporting the metal plate to be etched designated 39. This metal plate is entirely insulated from the supporting frame. The 50 metal plate is held rigid from either longitudinal or transverse movement by the supporting frame and the tool controlling head which is mounted upon the ram 10 reciprocates back and forth over 55 the metal plate to be etched and is given a lateral traverse over this metal plate. The tool controlling head in the form of my invention illustrated in Figure 2 includes a field magnet having a core 40 of soft iron surrounded by a 60 coil or winding 41. The core 40 extends upward at its center as at 42 and disposed above this end of the field magnet is an armature designated 43 which extends down around the central hub 42 of the core and includes windings 44. The coil 41 is connected by wires 45 and 46 to a 65 source of field coil current, as will be later explained, while the core of the float armature 43 is connected by wires 47 and 48 to a radio amplifier as will be later stated. The core 40 has a 70 central bore and extending downward through this bore is a stem or rod 49 which at its upper end is supported by a leaf spring 50 carried by a post 51 projecting from the casing 52 which encloses the field magnet 40 of the armature 43. Supported upon the lower end of this rod 49 is a

supporting member 53 which at one end is carried upon a leaf spring 54 in turn mounted upon a bracket 55 attached to the casing 52. This member 53 carries at its outer end an electromagnet or solenoid coil 56 having a core 57. 5 Also mounted upon the member 53 and extending longitudinally beneath the coil 56 is a leaf spring 57a and carried upon this leaf spring is an upwardly and forwardly extending armature 58 facing the inclined end face of the core 57 and 10 coacting therewith. This armature carries upon it a clamp 59 upon which a metallic arc forming stylus 60 is mounted, this stylus normally engaging against the face of the plate 39.

When the coil 56 is energized, however, the 15 armature will be raised from the face of the plate carrying with it the stylus 60. An arc is formed between the end of the stylus 60 and the face of the plate when this occurs.

The metallic plate 39 to be etched is connected 20 by a wire 61 to a source of direct current. The coil 56 is also connected by a wire 62 to the source of direct current but through a carbon pile rheostat designated generally 63. This rheostat as usual includes a series of carbon disks disposed 25 within an outer casing and from the rheostat 63 extends a wire 64 to the source of current, as before stated. When the disks are loosely engaged with each other, the resistance of this rheostat is increased and when the disks are forced 30 against each other, the resistance is decreased.

For the purpose of compressing these disks and thus reducing the resistance of the rheostat, I provide a lever 65 having a plunger 66 which engages the lower disk of the series in the rheostat, 35 the inner end of this lever being provided with teeth 67. Attached to the member 53 is a rack 68 having teeth engaging the teeth 67. Thus as the member 53 is raised, the resistance of the rheostat will be increased and as the member 53 40 is lowered, the resistance of the rheostat will be reduced.

Disposed beneath the negative 37 is a lamp 69 whose rays are focused upon the negative or upon the negative plane and disposed above the 45 negative 37 is a phototron 70 which is electrically connected through amplifying means to the floating armature 43. Thus variations of light caused by different densities in the negative will 50 cause the photo-electric cell or other light-sensitive element 70 to vary the electric current passing through the coils of the floating armature 43.

Impulses controlled by the scanning device, that is, by the phototron are transmitted and amplified in the radio amplifier shown diagrammatically in Figure 1 and are used to energize this floating armature. The poles of the fixed field magnet 40 and the floating armature have the same polarity and thus any increase in the energy passing through the negative will cause the armature to be repelled by the field coils and this causes the member 53 to rise and lift the stylus 60 from the surface of the plate 39 and at the same time causes the disks of the carbon pile rheostat to be separated which increases the resistance in the electrical circuit which includes the rheostat, the magnet 56, the stylus 60, the plate 39 and the wire 61. The moment that the current passes into the coil 56, the armature 58 will be attracted to the core 57, lifting the stylus 60 70 from the face of the metal plate 39 so that the circuit is broken. As it is broken, an arc is made between the stylus 60 and the plate 39 and the difference in the resistance due to the difference in the height that the member 53 is raised, de- 75

termines the size of the pit that the arc burns in the plate 39. This arcing is only momentary and as soon as the circuit is broken, the armature 58 is released from the core 57 and the stylus drops 5 and makes another contact with the plate. As soon as this occurs, the circuit is again completed, the armature and the stylus are again raised and again an arc is formed. Thus a series of recesses or pits will be burned in the face of the 10 plate, the size of these pits depending upon the intensity of the arc.

When a dark portion of the negative is being scanned, a relative weak current flows through the field coils 41, so that the armature 53 and the 15 stylus are drawn upward but a short distance. This increases only slightly the resistance of the rheostat 63 and current passes through the local circuit 64, 63, 62, 56, 57a to the stylus, across the gap of the arc to the plate 39 and back by wire 20 60, 61, this circuit being immediately broken, however. The passage of relatively slight current through the field coils 44 causes a relatively slight lifting of the stylus and this causes a short but intense arc to be formed which burns a deep 25 and wide crater in the face of the pit, or a series of these craters, which, if the craters overlap, causes this portion of the face of the plate to be entirely burned out, as if routed out and provides a white printing surface. When a light portion 30 of the negative is being scanned, a relatively strong current flows through the field magnet 44 causing a greater lifting of the armature 53, a greater increase in the resistance of rheostat 63 and less current flows through the local circuit 35 of the stylus so that only a relatively small diametered pit or series of pits are formed by a longer arc of less intensity. This provides a nearly black printing surface and if the negative is so thin that the stylus is entirely lifted and held lifted, the printing surface will be unpitted and will provide an absolutely black printing surface.

If the entirely transparent portion or white portion of a negative permits the passage of considerable current to the floating armature, the armature will be held raised, the stylus will be supported entirely above the face of the plate 39 and this portion of the plate will, therefore, print a solid black. It will thus be seen that my structure provides for engraving the plate so that the plate will reproduce either solid white or solid black or intermediate tones in between the solid white and solid black.

It will be seen that when the stylus leaves the 55 plate, an arc is made the intensity of which is determined by the tone value of the negative. Where the negative is darker, the arc is intense and burns out more of the surface. In the lighter places, a contact is still made but a smaller arc occurs and a smaller pit is burned in the plate. This is due to the action of the floating armature operating the carbon pile rheostat which takes its current from a battery or other power source.

60 After a line of pits is burned in the plate on one longitudinal stroke of the ram, the traverse feed moves the negative and also moves the tool head with stylus 60 one step laterally and another line of pits is burned and so on until the plate is completed. The mechanism which I have above described is particularly applicable in line cuts, that is, cuts in which pure black and pure white are used but is not adapted to the reproduction of half tones.

65 In Figure 4, I illustrate a modification of the

mechanism previously described which is intended for the reproduction of half-tones or, in other words, photographs. The ram 10 in this instance carries upon it a coil 71 constituting a solenoid and extending through this is a core 72 constituting a stylus or etching element, the lower end of which is pointed. A spring 73 urges this stylus upward. When the coil 71 is energized, the stylus is forced downward. The coil 71 is intermittently energized through a circuit, the wires of which are designated generally 74 and which includes within it an interrupter 75 of any suitable character which mechanically interrupts the passage of current to the coil. The circuit which includes the interrupter and the coil is connected to a source of direct current. It will be seen that with this construction, the stylus is continually reciprocating toward and from the plate 37. The stylus or core 73 is connected by a wire 76 to the carbon rheostat 77 and to a battery 78 or other source of current, the wire from the other pole of this battery being connected to the plate 37. Associated with the rheostat 77 is the control head previously described and including the field magnet 40 and the floating armature 43 supported by the spring 50. A spindle 49 extends from the armature downward through the field magnet and is connected to a resilient arm 53a which is directly connected to a plunger 66a and corresponding to arm 33 and plunger 66. 30 The floating armature has its wires connected to the amplifying circuit and controlled by the photo-cell 70.

In the operation of this mechanism, the interrupter 75 is such as to make a certain number of contacts per inch as the stylus 72 moves across the plate. Thus the stylus is being continuously reciprocated toward and from the plate 37. When the stylus leaves the plate, it makes an arc, the intensity of which is determined by the tone value 40 of the negative which in turn, of course, controls the floating armature 43 and controls the degree of compression of the carbon in the rheostat 77. In those places where the negative is the darkest, the arc is intense and burns out more 45 of the surface of the plate. In the light places, a contact is still made but a smaller arc occurs and a smaller pit is, therefore, burned. After a line of pits is burned in the plate on one stroke of the ram, the traverse feed moves the ram with 50 its coil laterally one step and another line of holes is burned and so on until the plate is completed. This construction makes a half tone plate from a photographic negative.

It will, of course, be understood that the tone 55 value of the negative is the reverse or opposite of the tone value of the engraved plate, that is, where the negative is dark or dense, the stylus will be lifted only slightly from the plate, a relatively large amount of current will flow through the stylus, and a relatively large pit will be formed. Where the negative is thin or light, the arc formed will be very short and have relatively slight intensity because of the slight amount of current flowing so that the plate will print either black at this point or with only a slight tone.

It is also to be understood that the guides 11 with the supporting frame 11a and allied parts slide laterally upon rails 89 or equivalent devices 70 under the action of the traversing screw 23.

It is to be understood that the means for reciprocating the ram and causing the lateral traverse of the ram are not part of the present invention as they are fully disclosed and claimed 75

in my prior application for patent before referred to.

Preferably the stylus will etch the plate only upon a stroke in one direction, the other stroke being idle. As illustrated in Figure 1, the stylus operates to etch the plate upon the backward stroke of the stylus, that is, a stroke toward the right hand in Figure 1 and in order that the stylus may be lifted while the stylus is traveling in a reverse direction, I provide a commutator designated generally 93 which may be mounted upon the shaft of gear wheel 34 to turn therewith or may be rotated by this gear wheel at the same speed as the gear wheel. The commutator has set into it the semi-circular sector of non-conducting material designated 94. Coacting with this commutator are the contact fingers 95 and 96 which are connected by conductors 97 and 98 to the amplifying system as shown in Figure 1. When the two contact fingers 95 and 96 both rest upon the metal of the gear 93 a circuit is completed which causes the stylus to be entirely lifted and held lifted while the ram 10 moves to the right in Figure 1. When one of the contact fingers 95, for instance, reaches the fibre part 94 of the gear, the circuit is broken and the tool lowered so that it can operate under the control of the negative as before described. Obviously the structure may be readily modified to etch upon the forward stroke of the ram or upon the rearward stroke of the ram as desired. In the construction illustrated, of course, the lateral traverse of the ram and of the etching stylus with the negative is secured upon the travel of the ram to the right in Figure 1.

As before stated, I electrically connect the phototron 10 with the floating armature 43 through an amplifying system by the wires 19 and 80 so that the impulses received from the phototron will be amplified when they affect the floating armature. Any suitable amplifying system may be used and I have here illustrated a direct coupled amplifying system diagrammatically. I have also illustrated the field coils 41 as being connected to a source of alternating current through a power transformer designated 90, the alternating current thus produced being rectified by the rectifier 91. I have also illustrated the radiotrons of the amplifying system as being supplied with current from a source of A. C. through a power transformer 92 having therein a rectifier 93. I do not wish to be limited to this, however. The rheostat 63 may be supplied with current from any suitable source of D. C. current.

It will be seen in each of the structures shown in Figures 1 and 4, the stylus rests upon metal and that it is intermittently and very rapidly raised and lowered and thus brought intermittently into contact with the metal plate as it travels across the face of the plate, thus making a series of momentary contacts. In each case, as the stylus raises, an arc is formed and the strength of the current forming the arc is controlled by the rheostat which in turn is controlled by the variations in light passing through the photo-cell 69. A series of pits are thus formed in the plate, which pits are shallow and small in diameter, where the current is reduced or deeper and larger in diameter, where the current is increased so that if these pits are very large and wide in diameter, they will overlap each other and the metal will be entirely burned away from that portion of the plate which is to print white, whereas if a portion of the plate is to print black, the pits will be relatively slight in depth and narrow in

diameter. Where the mechanism shown in Figure 4 is being used for the purpose of reproducing half-tones, tones between solid black and solid white will be secured by variation in the depth and diameter of the pits produced by the arc. 5

While I have illustrated certain mechanism which I have actually tested and which will produce the results called for, I do not wish to be limited to this mechanism as it may be varied in many ways without departing from the principle 10 of the invention as defined in the appended claims.

I claim:

1. A method of forming a metal printing plate which consists in traversing a stylus across the 15 face of the plate, in contact therewith, the metal plate and the stylus being in circuit with a source of current, causing the stylus to rapidly reciprocate against the face of the plate while it is traversing the plate, and varying the current 20 passing into the stylus and across the gap to the plate in accordance with variations in the light and shade of a pattern.

2. A method of forming a printing plate which consists in traversing a stylus across the face of 25 the plate in contact therewith, the metal plate and the stylus being in circuit with a source of current, causing the stylus to rapidly reciprocate against the face of the plate while it is traversing the plate, and varying the current 30 passing into the stylus and across the gap to the plate in accordance with variations in light passing through a light-sensitive element.

3. A method of forming a printing plate which consists in traversing a stylus across the 35 face of the plate in contact therewith, the plate and stylus being in circuit with a source of current, rapidly and intermittently lifting the stylus from the face of the plate and as the stylus is 40 lifted, varying the current passing into the stylus and across the gap to the plate in accordance with variations in the light and shade of a pattern.

4. A method of forming a metal printing plate which includes traversing a stylus across the face 45 of the plate, passing electric current through the stylus and plate, lifting the stylus varying distances from the plate at intervals by the action of light affected by the light and shade of a controlling picture to thereby form arcs between 50 the stylus and plate, and varying the current passing through the stylus and across the gap to the coacting plate in accordance with the distance that the stylus is raised from the plate.

5. A method of forming a metal printing plate, 55 which includes traversing a stylus across the face of the plate, passing an electric current through the stylus and plate, lifting the stylus varying distances from the plate at intervals by and in correspondence with the action of light 60 affected by the light and shade of a controlling picture to thereby form arcs between the stylus and plate, and reducing the current passing through the stylus and across the gap to the coacting plate in proportion to the distance that the 65 stylus is lifted from the plate.

6. A method of forming a metal printing plate which consists in causing a stylus to travel across the face of a plate, the stylus and plate being connected to a source of current, intermittently lifting the stylus from the plate to form an arc between the plate and the stylus, and varying the strength of said arc in accordance with variations in the conductivity in a 70 photo-cell. 75

7. Means for forming a metallic printing plate including a stylus normally resting upon and disposed in an electric circuit with the plate, means for traversing the stylus over the plate, means for rapidly and intermittently lifting the stylus from the plate while the plate and stylus are relatively moving to form arcs between the plate and stylus, and means for varying the strength of the arcs in accordance with a pattern to be reproduced upon the plate. 10
8. Means for forming a metallic printing plate including a stylus normally resting upon and disposed in an electric circuit with the plate, means for traversing the stylus over the plate, means for rapidly and intermittently lifting the stylus from the plate to form arcs between the plate and stylus, and means for varying the strength of the arcs in accordance with a pattern to be reproduced upon the plate including a rheostat and light operated means for controlling the resistance of said rheostat. 15
9. Means for forming a metal printing plate including a reciprocatable plate support, means for reciprocating the plate support, means for shifting the support laterally after each reciprocation, a stylus connected in an electric circuit with the plate on said support, means for causing the stylus to be intermittently lifted from and lowered into contact with the plate as the stylus is traversed over the face of the plate, and means acting as the stylus is lifted to vary the current in said circuit in accordance with variations in light and shade of a pattern to be reproduced. 20
10. Means for forming a metal printing plate including a reciprocatable plate support, means for reciprocating the plate support, means for shifting the support laterally after each reciprocation, a stylus connected in an electric circuit with the plate on said support, means for causing the stylus to be intermittently lifted from and lowered into contact with the plate as the stylus is traversed over the face of the plate, and means acting as the stylus is lifted to decrease the current passing through said circuit between the stylus and the plate in proportion to the height to which the stylus is raised and in accordance with variations of light and shade in a pattern. 25
11. Means for forming a metal printing plate including a plate support and a stylus, means for relatively shifting the support and stylus to carry the stylus in a plurality of directions over the face of the plate, means electrically connecting the stylus and the plate in circuit with a source of energy, means for intermittently lifting the stylus from the plate and lowering it into contact therewith as the plate and stylus are relatively traversed to form arcs between the stylus and the plate, and means for varying the strength of said arcs by and in accordance with variations in the light and shade of a pattern. 30
12. Means for forming a metallic printing plate including a plate support, a stylus coacting with the plate, means for causing the stylus and plate to move in a plurality of directions relative to each other to carry the stylus over all portions of the face of the plate to be engraved, means for electrically connecting the stylus and the plate in circuit with a source of energy, means for intermittently lifting the stylus from the plate to form arcs between the stylus and the plate, and means for varying the current in the circuit of the plate and stylus including a carbon rheostat and means controlled by variations in the light 35
- and shade of a pattern to be reproduced controlling said rheostat. 5
13. Means for forming a metallic printing plate including a plate support, a stylus coacting therewith and normally resting upon the plate, means for causing relative movement between the stylus and the plate in a plurality of directions to thereby cause the stylus to traverse over all portions of the face of the plate, means for causing the stylus to be intermittently lifted from and lowered into contact with the plate as the stylus and plate are traversed relative to each other, a carbon rheostat in said circuit, a field magnet, an armature yieldingly supported in coactive relation to the field magnet and having a coil, the armature being operatively connected to the plunger of the rheostat, and means for varying the current passing through the coil of the armature by and in accordance with light and shade in a pattern. 10
14. Means for forming a metallic printing plate including an insulating support for the plate, a stylus, means for causing the stylus to traverse over and in normal contact with all portions of the plate to be engraved, the stylus being mounted for vertical movement away from the face of the plate but being urged against the plate, an armature carried by the stylus, an electro-magnet associated with the armature, a carbon rheostat, the electro-magnet, the rheostat, the stylus and the plate being connected in circuit with a source of current, a field magnet having a coil connected in circuit with a source of current, an armature for the field magnet and having the same polarity thereas, means yieldingly supporting the armature in spaced relation to the field magnet, means for supporting the stylus and its associated magnet from the armature, and means operatively connected to the floating armature and to the rheostat acting to increase the resistance of the rheostat as the stylus is withdrawn from the surface of the plate. 15
15. Means for forming a metal printing plate including a stylus resting on the plate and disposed in a circuit with the plate and a source of energy, means for traversing the stylus relative to the surface of the plate, means for intermittently lifting the stylus from the plate while the plate and stylus are relatively moving to form successive arcs between the plate and the stylus, a light-sensitive element, means for scanning a picture by the light-sensitive element, and means controlled by the light-sensitive element for varying the intensity of successive arcs. 20
16. Means for forming a metal printing plate including a reciprocatable plate support, means for reciprocating the support, means for shifting the support laterally after each stroke in one direction, a stylus connected in an electric circuit with said plate on said support, means for causing the stylus to be intermittently lifted from and lowered into contact with the plate as the stylus is traversed over the face of the plate, means acting as the stylus is lifted to vary the current in said circuit in accordance with variations in light and shade of a pattern to be reproduced, and means for rendering the stylus inoperative upon a movement of the stylus in the opposite direction. 25
17. Means for forming a metal printing plate including a reciprocatable plate support, means for reciprocating the plate support, means for shifting the support laterally after each stroke of the plate support in one direction, a stylus connected in an electric circuit with the plate on said support, a solenoid surrounding said stylus and 30

of which the stylus is the core, means urging the stylus upward, means for intermittently breaking the circuit through said solenoid to thereby cause a vertical reciprocation of the stylus toward and from the plate as the stylus is traversed over the face of the plate, and means acting as the stylus is lifted to vary the current in said circuit including the plate and stylus in accordance with variations in the light and shade of a pattern to be reproduced.

18. A method of forming a metal printing plate which includes traversing a stylus across the face of the plate, passing a current through the stylus and plate, intermittently lifting the stylus from the plate while the plate is being traversed relative to the stylus to thus form a series of successive arcs between the plate and the stylus and modulating the current passing between the stylus and plate in accordance with variations of a pattern.

19. A method of forming a metal printing plate by pitting the surface of the plate which consists in subjecting the printing plate to the action of rapidly successive electrical arcs along a two-dimensional scanning pattern, and varying the strength of the arcs in accordance with variations of light and shade in said pattern.

20. Means for forming a metal printing plate by pitting the surface of the plate including a stylus electrically engaging the plate, means for traversing the plate and stylus relatively to each other, means electrically connecting the plate and stylus, means for intermittently forming rapidly successive arcs between the plate and stylus as the plate is moved and means for simultaneously varying the strength of the arc in accordance with a pattern to be reproduced upon the printing plate.

21. A method of forming a design upon the surface of a metallic plate which includes traversing a stylus across the face of a plate, passing an electric current through the stylus and plate while intermittently lifting the stylus from the

face of the plate, and modulating said current by current from an extraneous source, the voltage of the current from the extraneous source being modulated by and in accordance with the light and shade of a pattern. 5

22. A method of forming a metal printing plate which includes pitting the surface of the plate uniformly in accordance with a two-dimensional scanning pattern by a series of electric arcs and modulating the strength of the arcs in accordance with the light and shade of the pattern to thereby form pits of greater or less depth and correspondingly greater or less diameter upon the face of the plate. 10

23. A method of forming a metallic printing plate including traversing a stylus across the face of the plate while intermittently lifting the stylus from the face of the plate and simultaneously passing current from a source of definite voltage through the plate and stylus, simultaneously projecting a light beam through a pattern while causing the beam to scan the pattern, employing variations in intensity in the light beam to vary current flow through an electric circuit, amplifying the said current flow, and employing the said amplified current to effect the intermittent lifting of the stylus from the face of the plate while it is traversing the same. 15 20

24. A method of producing a metallic printing plate from a picture including traversing the stylus across the face of the metal plate while intermittently lifting the stylus from the face of the plate and simultaneously passing current from a source of definite voltage through the plate, effecting the modification of a beam of light by the variations in the tonal value of the picture, employing the modifications of said light beam to vary current flow in an electric circuit, amplifying the current variations in said circuit, and effecting the modulation of the current passing through the plate and stylus by the amplified current of said circuit. 30 35 40
